UNITED STATES PATENT OFFICE.

HARRY C. BUHOUP, OF CHICAGO, ILLINOIS, ASSIGNOR TO THE McCONWAY & TORLEY COMPANY, OF PITTSBURGH, PENNSYLVANIA, A CORPORATION OF PENNSYLVANIA.

CAR-COUPLING.

1,036,556.

Specification of Letters Patent. Patented Aug. 27, 1912.

Application filed September 13, 1911. Serial No. 649,132.

To all whom it may concern:
Be it known that I, HARRY C. BUHOUP, a citizen of the United States, residing at Chicago, in the county of Cook and State 5 of Illinois, have invented certain new and useful Improvements in Car-Couplers; and I do hereby declare the following to be a full, clear, and exact description of the invention, such as will enable others skilled in the art to which it appertains to make and 10 use the same.

My invention relates to the construction of car couplers of the vertical plane type and more especially to that class of couplers 15 in which the coupler head is yieldingly attached to the car body by a plurality of draft stems that are pivotally connected to the coupler head.

The object of my invention is to provide 20 a simple, compact, easily operated, strong and durable coupler which is adapted to be connected to the car body by a plurality of draft stems and which may be provided with a vertically sliding gravity lock, a knuckle 25 opener actuated by such lock and a supplemental lock, or so-called lock-to-the-lock, for preventing the accidental unlocking of the coupler when the car to which it is attached is in service.

30 In the construction of car couplers which are yieldingly connected to the car body by a plurality of draft stems, it is desirable that the coupler head shall be of small di-

that of an adjacent car, drags upon the track and is apt to be torn from the car.

By the construction and combination of the parts hereinafter described a coupler head of comparatively small dimensions 60 serves to furnish a support and to coöperate with a knuckle, lock, knuckle-opener mechanism and lock-to-the-lock devices, the construction, therefore, being particularly well fitted for the type of couplers heretofore 65 mentioned in which the coupler head is yieldingly connected to the car body by means of a plurality of draft stems.

In the drawings chosen for the purpose of illustrating the invention, the scope whereof 70 is pointed out in the claims,

Figure 1 is a plan view of a three-stem coupler embodying my invention; Fig. 2 is a horizontal central section of the coupler head shown in Fig. 1, the knuckle and 75 knuckle-opening device being shown in plan and the parts being shown in locked position; Fig. 3 is a vertical section taken on the line 3—3, Fig. 1; Fig. 4 is a side elevation of the devices shown in Fig. 1, a portion 80 of the coupler head and knuckle being broken away to show the knuckle-opening device; Fig. 5 is a detail side elevation of the coupler lock, the means for engaging 85 and actuating the knuckle-opener being omitted; Fig. 6 is a detail front elevation of the coupler lock together with the knuckle- 85 opener actuating means carried by said lock;
